UNITED STATES PATENT OFFICE.

MICHAEL F. DRISCOLL, OF WEST SPRINGFIELD, MASSACHUSETTS.

PIPE-WRENCH.

1,223,680.

Specification of Letters Patent. Patented Apr. 24, 1917.

Application filed December 29, 1916. Serial No. 137,995.

To all whom it may concern:

Be it known that I, MICHAEL F. DRISCOLL, a citizen of the United States, residing in West Springfield, county of Hampden, 5 and State of Massachusetts, have invented certain new and useful Improvements in Pipe-Wrenches, of which the following is a specification.

This invention relates to improvements in 10 pipe wrenches of the type in which the gripping jaws are formed with a plurality of teeth arranged in the form of a circle, whereby the pressure that is exerted on the pipe on its opposite sides will be very nearly 15 equalized, thus preventing injury or denting the pipe or other object which is being gripped by the wrench.

Heretofore in wrenches of this class the jaws have not had the teeth symmetrically 20 arranged so as to exert uniform pressure resulting in the denting of the pipe.

A further object of the invention is to provide means for holding the usual thumb nut against movement after the jaws have 25 been clamped to a pipe.

Referring to the drawings:

Figure 1 is a side elevational view showing the jaws open and in the act of gripping the pipe, also illustrating the adjusting thumb nut with the grooves in one end thereof, 30 which grooves are designed to receive the end of the holding plate;

Fig. 2 is a sectional end elevation of the movable jaw and illustrating the grooves in 35 the end of the adjusting nut; also the slide which engages the grooves.

Referring to the drawings in detail: 1 designates the handle part of the wrench having the integral jaw portion 2. 3 is the 40 movable jaw part of the wrench that is provided with the usual threads 4 on the shank thereof. The part 3 is formed with a plurality of teeth 5 and the part 2 is formed with a plurality of teeth 6. It will be noticed 45 that these teeth are arranged in the form of a circle. A pipe is conventionally illustrated at 7 in dotted lines and shown as being uniformly gripped by the teeth 5 and 6. The location of these teeth in the form 50 of a circle causes them to engage the pipe 7 at equally spaced points, whereby when the wrench is operated to turn the piece of pipe a uniform pressure will be exerted on the pipe. Another purpose for arranging the 55 teeth of the jaws in a circle is for the purpose of causing the wrench to hang on a pipe

after it is once applied. If the jaws of the wrench are parallel the wrench will drop off. In many places where the workman is obliged to apply the wrench with one hand, 60 that is to say, to open and close the jaws, it is a great convenience to have the tool hang on the article after it is applied. In order to lock the movable jaw 3 against movement after being adjusted the yoke 8, which is 65 pivoted to the handle 1 at 8', is provided with parallel arranged integral overhanging parts or lips 9 and located between these parts or lips 9 is the slidable plate 10 which is formed with the longitudinal opening 11 70 therein. A thumb screw 12 is used to retain the slide 10 in fixed position. This slide is designed to engage the grooves 13 in the end of the adjusting nut 14, whereby the movable jaw 3 is retained against movement. 75 It will be noticed that the grooves 13 are arranged substantially tangentially to the opening through the nut 14 in order that they may lie in a plane parallel with the face of the yoke 8 on which the slide 10 is 80 mounted. It is, of course, obvious that other changes in construction may be employed for retaining the nut 14 against movement but the present device is believed to be the simplest and one that will effectively hold 85 the nut 14 against movement.

In adjusting the wrench the slide 9 is drawn away from the nut 14 and out of the grooves 13. This nut is then rotated to adjust the movable jaw 3 into close contact 90 with the pipe 7. The slide 9 is then pushed forward into one of the nearest grooves 13 of the nut, whereby the jaw is retained in fixed position during the operation of turning of the pipe or other article. 95

It will be seen that I have provided a pipe wrench that is capable of quick and reliable action and one which retains the movable jaw in a fixed position during the operation of the tool. 100

What I claim is:

In a pipe wrench the combination, of fixed and movable jaws, the jaws having teeth arranged in the form of a circle to place uniform pressure on the article to be 105 gripped and to prevent the wrench from becoming detached from the pipe when it hangs in a vertical plane, the movable jaw being mounted in a yoke which is pivotally secured to the fixed handle part of the 110 wrench, threads on the movable jaw, a nut having an opening therethrough and engag-

ing the threads for adjusting the same, and means for locking the nut, said means comprising grooves in the end of the nut and arranged tangentially to the opening in the 5 nut, a slide, a U-shaped guide-way secured to the yoke to receive the slide and located adjacent the grooves in the nut, said slide

engaging the grooves, and means for adjusting and clamping the slide in the guide-way, whereby the movable jaw is held in a 10 fixed position during the operation of turning the pipe.

MICHAEL F. DRISCOLL.
